UNITED STATES PATENT OFFICE.

DAVID S. THOMAS, OF NORTH PLATTE, NEBRASKA.

WINDMILL.

SPECIFICATION forming part of Letters Patent No. 236,859, dated January 18, 1881.

Application filed May 10, 1880. (No model.)

To all whom it may concern:

Be it known that I, DAVID S. THOMAS, of North Platte, in the county of Lincoln and State of Nebraska, have invented a new and Improved Windmill, of which the following is a specification.

The object of this invention is to provide an improved device for controlling or adjusting the sails or vanes of a windmill.

10 The invention consists of a clutch wheel or spider and of a spirally-grooved loose sleeve (the latter having a small vane attached) fixed on the axle of the wind-wheel, which sleeve engages with a stud, and being turned in one direction draws the wind-wheel inward to clutch with the spider, whereby the vanes of the former are set to the wind, said vane on the loose sleeve serving also as a means for adjusting or throwing flat the vanes of the wind-wheel in a

20 high wind.

Figure 1 is a partly-sectional side elevation of a windmill, showing the device attached. Fig. 2 is a perspective view of the hub of the wind-wheel. Fig. 3 is a perspective view of 25 the hub of the clutch-spider. Fig. 4 is a horizontal section of a portion of the wind-wheel hub and clutch-spider hub, showing their engagement with each other; and Fig. 5 is a plan view of the turn-table with the vane and wind-wheel broken away.

30 Similar letters of reference indicate corresponding parts.

In the drawings, A represents the standard supporting the wind-wheel and attachments, 35 on the top of which standard A is the thimble or support B, on which the turn-table C turns. From the rear end of this turn-table C the directing-vane D projects, while on the front of said turn-table C are fixed the outer and inner 40 journal-boxes, E F, respectively.

G is the axle, journaled in said boxes E F, and having keyed or otherwise secured on its outer end the wind-wheel H, whose vanes or sails h h turn loosely on the spokes m m. The 45 hub of said wind-wheel H is provided on its inner face with projecting studs n n, that are designed to engage in the sockets o o in the face of the hub of the opposite spider, K. Said spider K is loosely fitted on the axle G, between 50 the wheel H and the outer journal-box, E, and

consists of a hub provided with radial spokes or rods p p, that are inclined outward to enable them, when it is desired, to engage against the sails or vanes of the wind-wheel H. The hub of this spider K is provided with sockets 55 o o, for the engagement therein of the studs n n of the wind-wheel H; or the wind-wheel may be provided with the clutch-sockets, and the spider with the corresponding studs; or other equivalent device may be employed for clutch- 60 ing the two together.

A sleeve, L, is placed loosely upon the axle G, and rests in the journal-box F, with its inner end against the shoulder r of the axle G, said sleeve L being provided with a spiral groove, 65 s, on its outside, and having firmly secured upon it a radial rod, t, carrying a small sail or vane, M.

The top or cover of the journal-box F is provided with an interiorly-projecting stud, u, 70 that engages in the groove s of the sleeve L.

On pulling the cord N that is fastened to the rod t the sleeve L is thereby turned, with the effect of moving the axle G and its attached wind-wheel H rearward, so that the studs n n 75 of said wheel are engaged in the sockets o o of the spider K, and the sails or vanes h h, turning against the rods p p of said spider K, are thereby set and held to the wind. If the cord N be released, a high wind operating 80 against the vane M will cause said vane M to turn back, moving the sleeve L with it, and thereby releasing the clutch of the wind-wheel H with the spider K, and consequently the sails or vanes h h will swing straight with the 85 wind.

The power of this windmill is applied to a pump or other mechanism by means of the crank P.

The vanes or sails of this device are designed 90 to be connected together by a band or ring fastened to their inner ends, so that they shall all move together.

Having thus described my invention, I claim as new and desire to secure by Letters Patent—

1. A windmill constructed substantially as herein shown and described, with wind-wheel H, provided with studs n n, spider K, provided with sockets o o, axle-sleeve L, provided with 100

spiral groove *s*, and vane and rod *M t*, and journal-box *F*, provided with stud *u*, as set forth.

2. In a windmill, the longitudinally-moving axle *G*, provided with a loose grooved sleeve *L*, and journal-box cover, provided with stud *u*, substantially as herein shown and described.

3. In a windmill, the combination, with the wind-wheel *H*, of the spider *K*, substantially as herein shown and described, the one being

provided with clutch-studs, and the other with corresponding sockets, as set forth.

4. As a means for adjusting the sails or vanes of a windmill, the spirally-grooved loose sleeve *L*, vane and rod *M t*, and fixed stud *u*, substantially as herein shown and described.

DAVID SHELDON THOMAS.
